UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,318,941.

Specification of Letters Patent. Patented Oct. 14, 1919.

Application filed November 27, 1916. Serial No. 133,701.

To all whom it may concern:

Be it known that I, SAMUEL B. WILLIAMS, Jr., a citizen of the United States, residing at Brooklyn, in the county of Kings and 5 State of New York, have invented certain new and useful Improvements in Telephone-Exchange Systems, of which the following is a full, clear, concise, and exact description.

This invention relates to emergency apparatus for telephone exchange systems.

The object of the invention is to safeguard the operation of such systems by providing means automatically responsive to any failure of the more important parts of the 15 organization for indicating the nature and location of the trouble and also for operating devices to restore the operativeness of the system.

In the present instance the invention is 20 illustrated in connection with a call distributing system of the type in which apparatus is automatically operated to distribute the calls from a large number of subscribers' lines to the connecting circuits

25 of a large number of operators' positions. In this specific embodiment the subscribers' lines may be divided into groups of 500, and the calls that originate in each group of 500 lines may be extended to the connecting cord

30 circuits of a number of operators' positions by means of a plurality of finder circuits, each of the finder circuits having a switch at one end for connecting with any one of the 500 lines and a switch at the other end

35 for connecting with any cord circuit of any of the plurality of operators' positions. The controlling circuits over which any calling line of the group appropriates to its own use any one of the finder circuits, and over

40 which the appropriated finder circuit gains access to any of the operators' positions at the time available, are common to all of the line circuits, finder circuits and operators' positions which are thus in operative relation

45 with each other. It therefore follows that anything which causes a failure of these common controlling circuits and their associated apparatus may tie up the calls from 500 lines. It is toward the safeguarding of

50 the operation of such a system with respect to the failure of the apparatus and circuits common to a large number of lines and interconnecting links that the present invention is directed.

55 Broadly stated, this result is accomplished

by providing devices that respond to any alteration of the electrical condition of the common controlling circuits, or to any change in the operative condition of the common controlling apparatus that continues for an 60 interval longer than the interval that such alterations or changes persist in the normal operation of the system, or that is unaccompanied by such changes as occur in the normal sequence of operation. In the normal 65 operation of the system the various stages of the operation follow each other at substantially definite time intervals. By associating with the controlling circuits and apparatus emergency devices each of which 70 is set to respond within a definite interval after a certain stage of the operation is reached, this interval being somewhat in excess of the normal interval required for reaching the succeeding stage of the operation, and causing the succeeding stage of 75 operation to block the operation of the device, the device operates only in case abnormal conditions arise.

A specific embodiment of the invention 80 in a preferred form is illustrated in the accompanying drawings in which Figures 1, 2, 3, 4 and 5, when arranged side by side in the manner indicated by the corresponding lines that extend to the margins of the 85 drawings, show diagrammatically the application of the invention to a telephone system of the call distributing type.

As illustrated in the drawing, the system is represented as comprising telephone lines 90 extending from stations, as A and A', to stationary terminals upon a line finder frame, these stationary terminals being adapted to be connected with by a plurality of line finder switches or elevators, as LF and LF'. Each line has associated with it a line relay 12 and a cutoff relay 11, and each of the groups of lines into which the whole number of lines served by the finder frame are divided, has associated with it certain group apparatus designated LG and LG'. The group apparatus is connected through the medium of conductors 57 and 58 with the starting apparatus, (see Fig. 2), which is common to all of the groups and to the 100 whole number of lines terminating upon the line finder frame. The common starting apparatus is connected through the medium of conductors 25, 26, 27, 28 and 29 with the apparatus of the group of finder circuits 105 110

F, F' and F² associated with the line finder switches or elevators, as LF and LF', which serve the whole group of lines. The finder circuits F, F' and F² terminate in cord selector switches or elevators, as CS and CS', and through the medium of these, operating under the control of the operator's selecting apparatus SF, the finder circuits are adapted to have their connections extended to 10 any one of the connecting cord circuits which extend in conductors 85, 86, 87 and 88 to the various operators' positions. The operator's selecting apparatus SF common to the entire group of finder circuits is brought into coöperative relation with the apparatus of the finder circuits through the medium of the conductors 70, 71, 72, 73, 74, 15 75 and 76. Each one of the connecting cord circuits of the group at each of the operators' positions may be equipped generally as indicated in Fig. 5, and may terminate in a plug 170 which in completing the connection, may be inserted in the multiple 20 spring-jack 14 of a line extending to called 25 subscriber's station A². The connecting cords of the various operators' positions have multiple connection with different cord selector frames like that which includes the cord selectors CS and CS', such multiple 30 connections for a second cord selector frame together with the common operator's selecting apparatus for that frame being indicated at SF'.

The apparatus and circuits for safeguarding and indicating failure in the common circuits and apparatus that coöperatively relate the lines with the finder circuits are shown in Fig. 2 of the drawing. The apparatus comprising the lamp 250, the relays 251, 252, 253 and 255 and the key 254 (Fig. 2) has to do with the safeguarding of the common conductors which link the line group apparatus with the starting apparatus. The apparatus comprising the lamp 260, the relays 261, 262, 255 and the key 263 has to do with safeguarding the part of the common starting control circuit which passes through the resting contacts of the relays 22, 23 and 65 to ground. The apparatus comprising the lamp 240, the relays 241, 242, 243, 244 and 245 and the key 246 has to do with the safeguarding of the system with respect to the operation of the common starting relay 22 and the coöperating parts of the finder circuits. The apparatus comprising the lamps 270 and 271 and the relays 272, 273 and 281 (see Fig. 4) has to do with the safeguarding of the common circuit over which the finder circuits are brought into operative relation with the common operator's position selecting apparatus. The apparatus comprising the lamps 280 and 271 and the relays 281, 282, 283, 284 and 285 has to do with the 60 65 safeguarding of the release of the common

operator's selecting apparatus. The lamps 290 and 291 and the relays 292, 293 and 294 have to do with safeguarding the common circuit over which each operator's position has operative relation with the corresponding position-selecting apparatus of the different selector frames. 70

The line finder switches LF, LF', and the cord selector switches CS, CS', may be substantially like the switch illustrated and described in Patent 1,177,044 to James L. McQuarrie, issued March 28, 1916. The line finder and cord selector switches are alike in all substantial respects. Each comprises a longitudinally movable shaft 1 carrying as many sets of brushes 2 as there are groups of stationary terminals to be engaged. To move the shaft up, an extension at the lower end of the shaft is brought into engagement with the constantly rotating power member 3 by means of an idler wheel operated by the up-drive magnet 32; and to move the shaft down, the extension is brought into engagement with the power member 4 by means of an idler wheel operated by the down-drive magnet 62. Normally the brushes of each of the sets 2 are apart so as to clear the associated terminals by means of a separating cam 5 located between the innermost brushes of the set. The cam 5 is rotatably mounted, and when rotated in one direction releases the brushes and permits them to engage the associated terminals. The tripping or releasing of the brushes is controlled by a number of trip magnets, as 16 and 17. Each of these 100 when energized rotates an associated trip rod 6 that extends transversely to the shafts 1 and carries as many trip yokes 7 as there are finder switches in the group. The trip rod in rotating brings all of its trip yokes 7 into position to operate the brush-controlling cams 5 of the corresponding sets of brushes on all of the sets, so that whichever of the finder switches is caused to move up has that set of brushes tripped that corresponds with the particular trip magnet 16, 17, that is at the time energized. When the finder switch that has been in use is returned to its normal position, any of the associated controlling cams 5 that has been tripped is 110 engaged and rotated in a reverse direction to separate its switch springs again and thus render them inactive. Each of the line finder and cord selector switches has associated with it a commutator 8 which comprises a number of stationary commutator segments and a set of movable brushes carried at the top of the switch shaft 1 and co-operating with the stationary segments. This commutator serves to make and break 120 a number of the controlling circuits in the various stages of the upward movement of the switch shaft. 125

For controlling the circuits of the organization, there are employed a number of se- 130

quence switches which are shown at different points and are designated 100, 200 and 300 respectively. These sequence switches may be of the type disclosed in Patent 1,127,808 5 issued February 9, 1916 to Reynolds and Baldwin. Each consists of an electromagnetically controlled motor or driving mechanism and a number of associated switch cams. The switch cams associated with each 10 of the sequence switches 100 are designated 101 to 103, inclusive; those associated with each of the sequence switches 200 are designated 201 to 222, inclusive; and those associated with each of the sequence switches 300 15 are designated 301 to 304, inclusive. To each of the contacts associated with the various sequence switch cams are applied certain numerals. These numerals in the case of the cams 101, 201 and 301 indicate the only 20 positions of the associated sequence switch in which these particular contacts are open; the numerals applied to all of the other contacts of each sequence switch indicate the only positions of the particular sequence 25 switch in which the associated contacts are closed.

The sequence switches 100 merely act as timing switches and have only one resting position. The resting positions of the other 30 sequence switches, and the stages of operation with which these positions are associated, are as follows.

Sequence switch 200.

- 35 1. Normal.
- 2. Awaiting starting circuit.
- 3. Awaiting starting circuit release.
- 4. Hunting calling line.
- 5. Awaiting preceding finder circuit.
- 40 6. Awaiting operator's selecting circuit.
- 7. Awaiting operator's selecting circuit.
- 8. Releasing operator's selecting circuit.
- 9. Hunting cord circuit.
- 10. Talking.
- 11. Line finder at tell-tale.
- 45 12. Line finder return.
- 13. Cord selector return.

Sequence switch 300.

- 50 1. Awaiting a call.
- 2. Position vacant.
- 3. Position busy.

The operation of the system as illustrated in the accompanying drawings is as follows:

55 When a subscriber calls, the taking of the telephone receiver from its hook closes a circuit in the usual way that causes the energization of the associated line relay 12 at the central office. The line relay in operating 60 closes a circuit that extends from battery through the winding of relay 19 of the group in which the calling line is located, contacts 103 (18 $\frac{3}{4}$ to 11) of sequence switch 100 of that group, group conductor 18, and armature and front contact of line

relay 12 to ground. Relay 19 in operating closes a circuit that extends from battery through the right-hand winding of relay 24, front contact and armature of relay 19, conductor 57, inner back contact and armature 70 of relay 22, left-hand back contact and armature of relay 23, back contact and armature of relay 65 to ground. Relay 24 in operating closes a locking circuit for itself in its left-hand front contact and armature, 75 and in doing so causes the operation of the associated tripping magnet 16, the energizing path for the tripping magnet and for the left-hand or locking winding of relay 24 being in parallel from battery by way of the left-hand front contact and armature of relay 24, conductor 58, winding of relay 22, left-hand back contact and armature of relay 23, and back contact and armature of relay 65 to ground. Relay 24 in operating 80 also closes a circuit that extends from battery through the motor magnet of the associated sequence switch 100, sequence switch contact 102 (18 $\frac{3}{4}$ to 11), and right-hand front contact and armature of relay 24 to 85 ground. The closure of this circuit moves sequence switch 100 out of position 1, whereupon the switch continues to rotate, under the control of its governing cam 101, until it completes its cycle and again comes to 90 rest in position 1. While the sequence switch 100 is rotating it maintains open in sequence switch contact 103 (18 $\frac{3}{4}$ to 11) the connection of the relay 19 with the group conductor 18, so that during this period the 100 relay 19 is not under the control of the line relay 12 of the corresponding group. During this interval the calling line is found and the line relay 12 deenergized to remove the ground from the conductor 18, as hereinafter to be described.

Included in the circuit by way of conductor 58 closed upon the initiation of a call, as described above, is the winding of the starting relay 22. This relay in operating 110 closes the circuit of the starting conductor 29, and in doing so brings about the movement of a line finder switch of one or another of the finder circuits F, F' or F². For reasons that will hereinafter be explained only one of the sequence switches associated with these finder circuits is in position 2. Assuming that this is the sequence switch of finder circuit F, a circuit is completed that extends from battery through 115 the left-hand winding of relay 30, sequence switch contacts 206 (2), conductor 29, inner front contact and armature of relay 22, left-hand armature and back contact of relay 23, and back contact and armature of relay 65 to ground. Relay 30 in operating closes a locking circuit for itself that extends from battery through resistance coil 56, sequence switch contacts 217 (2 to 9), right-hand winding of relay 30, sequence switch 120 125 130

contacts 216 (2 to 4) and (2 to 9), left-hand front contact and armature of relay 30, and armature and back contact of relay 37 to ground. Relay 30 also closes a circuit that extends from battery through the motor magnet and cam 202 (2) of sequence switch 200, right-hand front contact and armature of relay 30, sequence switch contacts 208 (18 to 14) and (2 to 7) to ground. 10 The closure of this circuit causes sequence switch 200 to move out of position 2 and come to rest in position 3.

In position 3 of the switch, a circuit is closed that extends from battery by way of 15 the up-drive magnet 32 of the corresponding line finder switch $L F'$, sequence switch contact 207 (3 to 4), front contact and right-hand armature of relay 30, and sequence switch contacts 208 (18 to 14) and (2 to 7) to ground. 20 The energization of the up-drive magnet 32 starts the upward movement of the corresponding elevator rod with its associated sets of brushes. At the outset of the upward movement of the elevator 25 rod all of the brush trip levers are moved past the corresponding trip yokes. The only trip magnet that is energized in this case is the magnet 16 which corresponds with the group in which the calling line is 30 assumed to be located; and consequently the only trip yoke in position to engage a trip lever on the elevator rod is the one which controls the brushes 40, 41, 42 and 43 that are adapted to engage the terminals of that 35 particular group of lines. This set of brushes therefore is released and made operative, and the other sets are held clear of their associated line terminals.

As soon as the set of brushes corresponding 40 with the calling line is tripped, the group apparatus, by means of which the lines control the brush tripping and line finder starting operations, may be returned to its normal condition. The first step in this 45 restoring operation is effected by the closure of a circuit which is completed by way of the K segment of the line finder commutator immediately after the brushes are tripped. This circuit extends from battery in parallel 50 branches through the relays 33 and 23 (see Fig. 2), conductor 26, sequence switch contact 209 (2 $\frac{3}{4}$ to 3), conductor 68, and to ground by way of the K segment of the line finder commutator and its associated brush. 55 The energization of the relay 23 interrupts, in the left-hand back contact of that relay, the previously described circuit that has up to this time maintained the energization of the trip magnet 16, the group relay 24 and 60 the common starting relay 22. Relay 23 in its right-hand front contact closes a locking circuit for itself and the associated relay 33 that extends by way of conductor 25 and the sequence switch contacts 210 (2 $\frac{3}{4}$ to 1) of 65 all of the finder circuits in series, to ground

at a point beyond the last switch of the series.

As has already been stated, normally there is only one of the finder circuits with its sequence switch in position 2 awaiting the 70 receipt of a call. When the call comes in this sequence switch is immediately moved to position 3, in the manner described above. Therefore, at this stage of the operation, the sequence switches of all of the finder circuits, being either in position 1 or in position 75 3 and beyond, are in position to close their contacts 210. The locking circuit for the relays 23 and 33 is therefore held closed until another one of the finder circuits has 80 its sequence switch moved into position 2 to break the locking circuit in the corresponding sequence switch contacts 210. This is accomplished by relay 33 which in operating applies a ground to conductor 28 to move the sequence switch of another finder circuit out of position 1 and into position 2, and which also applies a ground to the conductor 85 27 to move the sequence switch of the appropriated finder circuit out of position 90 3.

Assuming that the sequence switch of finder circuit F' is in position 1, and that the sequence switch of finder circuit F^2 is in some position between 4 and 17, that finder 95 circuit being assumed to be in use, the operation of the relay 33 completes a circuit from battery through the motor magnet and contacts 203 (1) of the sequence switch of finder circuit F' , contacts 211 (1) of the same sequence switch, contacts 211 (3 to 17) and (4 to 17) of the sequence switch 200 of finder circuit F^2 , contacts 212 (3 to 17) and (3 to 3 $\frac{1}{4}$) of the sequence switch 200 of finder circuit F that has just been appropriated, conductor 28, and left-hand front 100 contact and armature of relay 33 to ground. This causes the sequence switch of finder circuit F' to move into position 2. At the same time the sequence switch of finder circuit F is moved out of position 3 by the closure of a circuit that extends from battery through the motor magnet and contacts 203 (3) of the sequence switch of that circuit, conductor 27, and right-hand front contact 105 115 and armature of relay 33 to ground.

As soon as the sequence switch of finder circuit F' moves into position 2, it opens in its contacts 210 the circuit by way of conductor 25 which up to this moment has 110 maintained relays 23 and 33 energized, and these relays thereupon release their armatures. Relay 23 in releasing reconnects to ground the circuit which extends in branches 57 and 58 through the various sets of line 115 group relays, thus again giving the line groups access to the starting circuit.

At this stage of the operation of the system the sequence switch of the appropriated finder circuit F is in position 4, and the ele- 120 125 130

vator of the associated line finder LF' is moving up with the set of brushes tripped that corresponds with the group in which the calling line is located. As the tripped 5 brushes rise they come into engagement successively with the sets of terminals corresponding with the different lines of the group. At the instant of engagement of the brush 42 with the corresponding line terminal 46 of each line, a circuit is closed that 10 extends from battery by way of the relay 52, sequence switch contacts 212 (2 to 4), conductor 50, brush 42, line terminal 46, conductor 53, and winding of cutoff relay 11 to ground. In case a line over which the 15 brushes are passing is busy, either as a calling or as a called line, a branch path from battery is closed to conductor 53 which serves to shunt the relay 52 and prevent its operation as the finder brushes pass over the 20 terminals of the corresponding line. In the case of the lines that are not busy, the relay 52 is operated as the brushes engage the terminals of such lines. In attracting its 25 armatures the relay 52 closes a circuit that extends from battery through the lower winding of the relay 37, front contact and inner armature of relay 52, sequence switch contact 213 (2 to 4), conductor 49, brush 41, line 30 terminal 45, conductor 39 to one limb of the telephone line, thence by way of the path controlled in contacts of the substation switchhook to the other limb of the line, conductor 38, terminal 44, brush 40, conductor 35 48, sequence switch contact 214 (2 to 4), upper armature and front contact of the relay 52, and upper winding of the relay 37 to ground. The circuit traced above is not completed until the finder switch brushes 40 engage the terminals of the calling line, for the reason that the calling line is the only line that has its telephone receiver off the hook and at the same time is not made busy by being connected with either by some 45 other line finder or by a connecting cord calling plug. The completion of this circuit energizes the relay 37 and causes that relay to interrupt in its back contact the circuit by way of the left-hand armature and front 50 contact of the relay 30, sequence switch contacts 216, right-hand winding of relay 30, sequence switch contacts 217, and resistance 56 to battery, which circuit has been holding relay 30 locked up from the moment that 55 the relay was first energized upon the receipt of the call.

Relay 30 in releasing its armatures breaks its own locking circuit traced above, and also breaks the previously traced path including 60 sequence switch contacts 208, right-hand front contacts of the relay 30, and sequence switch contacts 207, over which current has been flowing to energize the up-drive magnet 32 of the line finder. Therefore the operation of the relay 37 upon the finding of

the calling line acts to effect the instant de-energization of the up-drive magnet 32 and thus to stop the brushes upon the terminals of the calling line.

When the relay 30 is deenergized, as a result of finding the calling line, it also completes a circuit that extends from battery through the motor magnet and contacts 202 (3 to 4) of the sequence switch 200, right-hand back contact and armature of the relay 70 30, sequence switch contacts 208 (18 to 14) and (2 to 7), to ground. The closure of this circuit moves the sequence switch out of position 4. When the sequence switch reaches position 4₄, it closes a path for the flow of 75 current through the cutoff relay 11 of the calling line by way of resistance coil 64, sequence switch contact 212 (4₄ to 12₁), conductor 50, brush 42, line terminal 46 and conductor 53. The flow of current in this 80 path operates the cutoff relay 11 to disconnect the line relay 12 from the circuit, and that relay in releasing its armature disconnects ground from the common conductor 18. The disconnection of ground from conductor 18 occurs before the timing sequence switch 100 has completed its cycle of rotation and reconnected conductor 18 with relay 19.

In the foregoing the normal operation of 95 the system has been described up to the time when the line finder switch of an unengaged finder circuit completes connection with a calling line. The operation of the part of the system that comes into action when an 100 emergency or abnormal condition arises in the circuits and apparatus controlling the above-described stages of operation will now be explained.

In order that the calling lines may have 105 control over the apparatus that energizes an idle finder circuit when any line calls, it is necessary that there shall be a normally continuous series circuit by way of the conductors 57 and 58 through the resting contacts 110 of the group relays 19 and 24 of the various groups. As long as this condition exists circuits are completed which hold the relays 251 and 252 energized. The circuit for the relay 251 extends from battery through the winding of that relay, thence by way of the conductor 58 and the left-hand back contact 115 and armature of each of the group relays 24 in series, the winding of the starting relay 22, left-hand back contact and armature 120 of relay 23, and right-hand back contact and armature of relay 65 to ground. The normal energizing circuit for the relay 252 extends from battery through the winding of that relay and thence by way of conductor 125 57 and the back contact and armature of each of the group relays 19, inner back contact and armature of starting relay 22, left-hand back contact and armature of relay 23, and right-hand back contact and armature 130

of relay 65 to ground. The winding of each of the relays 251 and 252 is of high resistance, the high resistance of the relay 251 preventing the current normally permitted 5 to flow through it from energizing the starting relay 22; but in each case the normal current flow is sufficient to keep the relays 251 and 252 energized and their armatures attracted. When the energizing circuit of 10 either of these relays is interrupted, the relay is deenergized and closes a circuit, subject to certain conditions that will herein-after be set forth, which extends from battery through the winding of relay 253, the 15 switch contacts of whichever of the relays 251 and 252 has released its armature, and the right-hand back contact and armature of relay 255 to ground. When this circuit is closed the relay 253 in its upper front contact 20 and armature closes a locking circuit for itself by way of the release key 254; and also closes the circuit that extends from battery through the common relay 134, the lamp 250, right-hand front contact and armature of relay 253, left-hand back contact and armature of relay 262 to ground. The closure of this circuit lights the lamp 250 and also energizes the relay 134 which may close 25 a circuit for operating the electromagnet 30 136 to give an alarm or bring about other appropriate action. When the illumination of the lamp 250 has been noted, or such action as is called for by the arising of the condition has been taken, the release key 35 254 is pressed to open the locking circuit and permit the release of the relay 253.

The operation as described above will result if either of the group conductors 57 and 58 has its continuity interrupted by the 40 arising of any abnormal condition in the circuit. If, however, the interruption of the conductors 57 and 58 is caused by the operation of any of the sets of group relays 19 and 24 by the initiation of a call in the 45 normal operation of the system, such interruption is accompanied by the actuation of the starting relay 22 as already described. This relay in operating closes a circuit that extends from battery through the winding of relay 50 151 and the outer front contact and armature of relay 22 to ground. Relay 151 in operating closes a circuit that extends from battery through the winding of relay 255, left-hand front contact and armature of 55 relay 151 to ground. Relay 255 in operating interrupts in its right-hand back contact and armature the path over which the relay 253 is energized when the switch contacts of either or both of the relays 251 and 60 252 are closed upon the interruption of the energizing circuits of these relays. The relays 251 and 252 are so constructed as to be slow in releasing their armatures, as by providing the cores of the relays with copper shells, and the relay 253 may similarly be

constructed and adjusted so as to be slow in attracting its armatures. The result is that in the normal operation of the system the relay 255 is operated to block or prevent the operation of the lamp controlling relay 70 253 before the slow-releasing relays 251 and 252 effect the closure of their switch contacts to permit it. But if the interruption of the continuity of conductors 57 and 58 is a continuing accidental interruption, and 75 not incident to the normal operation of the systems, such interruption is not followed by the operation of the relay 22, the relay 255 is not operated to prevent the energization of the relay 253, and that relay operates to light the lamp 250.

Further, to prevent the lamp 250 from being lighted in the normal operation of the system, the blocking relay 255 is also energized by the operation of the relay 23. 85 When the relay 23 operates as a result of the starting of the finder switch, as already described, it opens in its left-hand back contact and armature the path to ground of the conductors 57 and 58. This releases the 90 starting relay 22, and that relay in releasing opens the energizing circuit of the relay 131, which in turn opens the path over which the relay 255 had theretofore been energized. But relay 23 in operating closes an 95 alternative energizing path for the relay 255 which extends by way of the left-hand front contact and armature of the relay 23 and the right-hand back contact and armature of relay 65 to ground. Therefore the relay 255 100 is held operated to prevent the closure of the energizing path for the relay 253, which energizing path would otherwise be closed on account of the deenergization of the relays 251 and 252, due to the interruption of 105 conductors 57 and 58.

Another condition that results in the release of the relays 251 and 252 in the normal operation of the system is that in which a call is initiated when all of the finder circuits that serve the group of lines in question are in use. When this condition arises, a circuit is completed that extends from battery through the winding of relay 135, conductor 80, and sequence switch contacts 215 110 (4 to 17) of all of the busy finder circuits in series, to ground at the end of the series. Relay 135 in operating closes the energizing circuit of the relay 133, the relay 133 in operating closes the energizing circuit of the relay 138, the last mentioned relay in operating closes the energizing circuit of the relay 139, and that relay in operating closes 115 the energizing circuit of the relay 65. The relays of this train perform other functions 120 with which the present invention is not concerned and which functions, therefore, are 125 not here described.

When the relay 65 operates, it opens in its right-hand armature and back contact the 130

normal connection with ground of the group conductors 57 and 58, this being for the purpose of preventing calling lines from energizing the starting relay 22 and the relay 24 and trip magnet 16 of the associated group, when none of the finder circuits is in condition to be used. The opening of the path to ground of the conductors 57 and 58 permits the deenergization of the slow-acting relays 251 and 252; but inasmuch as the opening of the conductors 57 and 58 is one that is incident to the normal operation of the system, the relay 255 is operated to open the circuit of the relay 253 controlled by the relays 251 and 252, and thus prevent the lighting of the emergency lamp 250. The energizing circuit of the relay 255 is from battery, through the winding of that relay, and to ground by way of the front contact and left-hand armature of the relay 65. Thus the relay 65, in preventing the operation of the starting apparatus, when all of the finder circuits are busy, also blocks and prevents the display of the emergency lamp 250.

The emergency lamp 260 and its associated controlling relays are for the purpose of indicating any accidental or improper opening in that part of the series group circuit that extends to ground by way of resting contacts of the relays 22, 23 and 65. The path by way of these relay contacts to ground normally short-circuits the winding of the high resistance relay 261. When this short circuit is interrupted, the relay 261 is energized by means of current that flows to its winding from battery by way of the winding of the relay 252, conductor 57, and the resting contacts of the relays 19 of the various groups. The relay 261 in operating closes, subject to the control of relay 255 in a manner hereinafter to be described, a circuit that extends from battery, through the winding of relay 262, armature and front contact of relay 261, and left-hand back contact and armature of relay 255 to ground. Relay 262 in operating closes, by way of its right-hand armature and front contact, a locking circuit for itself that includes the normally closed contacts of the release key 263. It also closes a circuit that extends from battery, through the winding of common relay 134, lamp 260, and upper front contact and armature of relay 262 to ground. The closure of this last mentioned circuit causes the illumination of the emergency lamp 260; and when appropriate action has been taken in response to the lighting of the lamp, the relay 262 may be released by operating the release key 263.

In order that the emergency lamp 260 may not be lighted when the short circuit is removed from relay 261 as a result of the normal operation of the system, the circuit 65 is so arranged that either of the relays 22,

23 and 65, in operating to break this normal short-circuiting path, also closes an energizing path for the relay 255, and the last mentioned relay in operating opens in its left-hand armature and back contact the ground connection of the lamp controlling relay 262. Thus, when the starting relay 22 is energized, it closes in its outer armature and front contact the energizing circuit of the relay 151, and that relay closes in its left-hand armature and front contact the energizing circuit of the relay 255, which operates, as described, to prevent the relay 261 from causing the energization of the relay 262. Again, when relay 23 in operating opens the normal short circuit of the relay 261, it closes in its left-hand armature and front contact the energizing circuit of the relay 255. Again, when the relay 65 in operating breaks the short-circuiting path of the relay 261, it closes in its left-hand armature and front contact the energizing circuit for the relay 255. But if the ground connection of the group conductors 57 and 58 is broken accidentally or abnormally, the relay 255 is not operated, and the actuation of the relay 261 causes the lighting of the emergency lamp 260.

It will be noted that the left-hand armature of the relay 262 controls in its back contact the energizing circuit of the emergency lamp 250, and controls in its front contact the energizing circuit of the emergency lamp 260. Therefore, if the interruption of the series group circuit including the conductors 57 and 58 is in that part of the circuit that extends through the resting contacts of the relays 22, 23 and 65, the energization of the relay 262 to light the emergency lamp 260 prevents the lighting of the emergency lamp 250 which would otherwise result from this same interruption. But if the break in the series group circuit is in that part which extends through the contacts of the group relays 19 and 24, the relay 262 is not operated, and the emergency lamp 250 is therefore lighted. Thus, one or the other of the lamps 250 and 260 is lighted to indicate in which part of the common series group circuit the accidental interruption exists.

As has hereinbefore been described, the starting relay 22 is actuated by a calling line to appropriate a finder circuit, and is released when the passing of the K segment, at the outset of the upward movement of the line finder switch, energizes the relay 23. As soon as the starting relay 22 is operated, it closes a circuit that extends from battery, through the winding of relay 241, right-hand back contact and armature of relay 243 and outer front contact and armature of relay 22 to ground. Relay 241 in operating closes a branch from battery of this same circuit that includes the winding 130

of relay 242. Relay 242 in operating closes another branch from battery of this same circuit that includes the winding of relay 243. Relay 243 in operating closes a locking circuit for itself by way of its right-hand front contact and armature, and also, in the back contact of its right-hand armature, opens the energizing circuit of the relay 241. Relay 241, in releasing its armature, opens the energizing path through the winding of the relay 242; and relay 242, in releasing, closes a path that extends from battery through the winding of relay 244, left-hand armature and front contact of relay 243 (which is now locked up), back contact and armature of relay 242, and to ground by way of the outer front contact and armature of starting relay 22. The relays 241 and 242 are so constructed and adjusted as to be slow in pulling up and slow in releasing. Consequently a considerable time interval elapses after the actuation of the starting relay 22 before the energizing path of the relay 244 is completed by the pulling up of the relays 241, 242, and 243 in series and the falling back of the relays 241 and 242. This interval is such that in the normal operation of the system, the starting relay 22 is released by the passing of the K segment and the energization of relay 23 before the slow-acting train of relays have acted to bring about the closure of the energizing circuit of relay 244. But if the release of the starting relay 22 is unduly delayed, the relay 244 operates and closes in its left-hand armature and front contact the energizing circuit of the relay 245. This relay in operating closes a locking circuit for itself by way of its armature and the release key 246, and also closes a circuit that extends from battery, through the winding of common relay 134, emergency lamp 240, switch spring and armature of relay 245, and normally closed contacts of release key 246 to ground. The closure of this circuit lights the emergency lamp, and when appropriate action has been taken the lamp may be extinguished and the relay 245 released by pressing the release key 246.

The relay 244 in operating as a result of an unduly delayed release of the starting relay 22, also closes a circuit that may cause apparatus to act automatically to remedy the condition responsible for the delayed release of the starting relay. This result is obtained by causing relay 244, when it operates, to apply a ground to the conductor 28 to move out of position 1 the sequence switch of another finder circuit in the same manner as relay 33 acts to bring about this result in the normal operation of the system, as hereinbefore described. Thus, if the delay in the release of the starting relay 22 has been due to the failure of the line finder

elevator, as LF', of the appropriated finder circuit to move up, the relay 244 responds to the abnormal condition and grounds conductor 28 to prepare another finder circuit for the use of the calling line.

The stages of the operation that are next to be described have to do with the selection by the appropriated finder circuit of an idle operator's position and the selection of an idle connecting cord on that position. When the finder sequence switch 200 reaches position 5, which it does as a result of being moved out of position 4 by the finding of the calling line as hereinbefore described, it closes a circuit that extends from battery by way of the winding of relay 55 (see Fig. 4), conductor 71, and sequence switch contact 218 (5 to 8) to ground. The operation of the relay 55 applies ground to the conductors 81 extending to all of the operators' positions to the connecting circuit terminals of which the cord selector switch of the finder circuit has access. At each of the positions where the operator is at her station and is in readiness to receive a call, the associated relay 91 (see Fig. 5) is inert and the operator's telephone sequence switch 300 is in its 1 position.

If the operator is listening in on a cord, the switch 415 associated with that cord circuit is closed, in any suitable manner, and an energizing circuit completed for relay 91. Likewise, if all of the connecting cords of a particular operator's position are in use, the entire series of switches 416, one of which is associated with each connecting cord-circuit, are closed and the relay 194 energized to complete an energizing circuit for the relay 91. In either case, the energization of the relay 91 renders the operator's position unselectable. Furthermore, when the operator is away from her station, the switch 122 is operated, in any usual or convenient manner, to complete a circuit that extends from battery, through the motor magnet and contact 303 (1 or 17) of the sequence switch 300, to ground by way of the resting contact and left-hand switch spring of the switch 122. The closure of this circuit moves the sequence switch to position 4, in which position sequence switch contact 304 (1) is open, and the position is consequently unselectable. When the operator takes her station, the levers of switch 122 are moved to the right, and a circuit is completed for the motor magnet of sequence switch 300 by way of contact 303 (4) and the alternate contact and right-hand switch lever of switch 122, which causes the sequence switch to move to position 1, its next resting position. In this position of the sequence switch the operator's position, subject to the control of relay 91, is rendered selectable by the closure of sequence switch contact 304 (1). At each position where

the relay 91 is inert and the sequence switch 300 is in position 1, as described, a circuit is closed that extends from battery, through the winding of associated relay 92, armature and back contact of relay 91, sequence switch contact 304 (1), conductor 81, armature and left-hand front contact of relay 55, to ground. The relay 92 of each awaiting available position, therefore attracts its 5 armature and closes a circuit that extends from battery, through the front contact and armature of relay 92, to the conductor 82, and thence to ground by way of the windings of the relays 77 at the various cord 10 selector frames as SF and SF'.

The finder circuit sequence switch 200 does not stop in position 5, but continues its movement and comes to rest in position 6. Here it awaits the closing of a circuit 15 the completion of which is dependent upon the condition of the other finder circuits of the associated group. This circuit extends from battery, through the left-hand winding of the relay 30, contact 219 (6) of the 20 appropriated finder circuit sequence switch, contacts 219 (9 to 4) of the sequence switches of the associated finder circuits preceding it in the series, conductor 76, outer armature and back contact of relay 25 54, and right-hand back contact and armature of relay 61 to ground. This circuit is open either in cam 219 of a preceding 30 finder sequence switch 200 in the series or in contacts of the relays 54 or 61 as long as 35 any other sequence switch of the series is in positions 4 to 9. That is, it is open from the time the line finder switch of any associated 40 finder circuits finds a calling line until the cord finder switch of that circuit has moved far enough to trip the brushes corresponding 45 with the selected group thus completing the operator's selection. Not until this has occurred, will the above traced circuit of the awaiting finder circuit be closed.

When this circuit is closed relay 30 attracts its armatures and completes a circuit that extends from battery, through the motor magnet and sequence switch contact 202 (6) of the sequence switch 200, front contact 50 and right-hand armature of relay 30, and sequence switch contacts 208 (18 to 14) and (2 to 7) to ground. The completion of this circuit moves the finder sequence switch out of position 6.

When the finder sequence switch reaches 55 position 6 $\frac{1}{2}$, it closes a circuit that extends from battery, through the winding of relay 54 (see Fig. 4), left-hand back contact and armature of relay 61, conductor 73, and 60 finder sequence switch contact 218 (6 $\frac{1}{2}$ to 8) to ground.

Relay 54 attracts its armatures and completes a branch of the circuit just traced, which extends from conductor 73 by way of 65 the armature and back contact of the relay

63, front contact and left-hand armature of relay 54, armature and front contact of the first relay 77 that is energized, as previously described, as a result of the corresponding operator's position being in readiness to receive a call, right-hand back contact and switch spring of relay 93 of the corresponding group, winding of associated relay 94, winding of relay 93, left-hand switch spring and back contact of relay 93, conductor 83, 70 left-hand back contact and armature of relay 95 at the operator's position, to battery. Upon the closure of the above traced branch circuit, the group relays 93 and 94 are energized in parallel with the relay 54. Relay 75 93 in operating disconnects its own energizing winding and that of associated relay 94 from the previously traced path to battery by way of the left-hand back contact and armature of the relay 95, and connects them 80 in a path which extends from battery by way of the winding of the relay 95 and conductor 84. This causes the relay 95 also to be energized and to interrupt in its left-hand armature and back contact the path by 85 way of conductor 83 over which the relays 93 and 94 were initially energized, and also to close a circuit that extends from battery by way of the motor magnet and contact 303 (1) of the operator's sequence switch, right-hand front contact and armature of relay 95 and right-hand contact and lever of switch 122 to ground. The closure of this circuit moves the operator's sequence switch through 90 position 4, and to position 17, where it remains until its motor magnet is energized by the operation of switch 192 or of 95 switch 122.

Relay 94 in operating closes a circuit from battery, through the winding of the trip magnet 20 corresponding to the selected operator's position, and to ground by way of the right-hand armature and front contact of the relay 94. This relay also closes a circuit that extends from battery, through the 100 winding of the relay 63 and the left-hand armature and front contact of the relay 94 to ground. The relay 63 in operating closes a branch that extends from the conductor 73 (grounded at contact 218 (6 $\frac{1}{2}$ to 8) of the 105 line finder sequence switch), through the armature and front contact of relay 63, conductor 72, sequence switch contact 220 (7), and left-hand winding of relay 30 to battery. Relay 30 attracts its armatures and 110 closes a circuit that extends from battery, through the motor magnet and sequence switch contact 202 (7), front contact and right-hand armature of relay 30, sequence switch contacts 208 (18 to 14) and (2 to 7), 115 and thence to ground. The closure of this circuit moves sequence switch 200 out of position 7. Furthermore, relay 30 in operating is locked up over a circuit that extends from battery, through resistance 56, sequence 120 125 switch contact 208 (18 to 14) and (2 to 7), and thence to ground. The closure of this circuit moves sequence switch 200 out of position 7. Furthermore, relay 30 in operating is locked up over a circuit that extends from battery, through resistance 56, sequence 130

switch contacts 217 (2 to 9), right-hand winding of relay 30, sequence switch contacts 216 (7 to 9) and (2 to 9), front contact and left-hand armature of relay 30 and armature and back contact of relay 37 to ground.

When the sequence switch reaches position 8, it closes a circuit that starts the upward movement of the brush carrying rod of the 10 cord selector switch, this circuit extending from battery, through the up-drive magnet 34 of the cord selector, conductor 89, sequence switch contact 207 (8 to 9), right-hand front contact and armature of relay 30, 15 sequence switch contact 218 (8 to 9), and thence to ground. At the outset of the upward movement of the cord selector brush rod, the tripping levers of the various sets of brushes are brought simultaneously into 20 operative position with respect to the corresponding trip yokes, and that set of brushes is tripped and made operative whose trip magnet is at the time energized. In the present instance, it may be assumed that this 25 is the trip magnet 20 associated with the terminals of the group of connection cord circuits extending to the 0 operator's position.

Immediately after the set of brushes is tripped, the common operator's selecting circuit 30 is restored so as to be available for the use of other cord finder switches. This is effected through the medium of a circuit that is completed by the grounding of the K segment of the cord finder commutator, this 35 segment being so located as to be engaged by its brush immediately after the tripping levers of the sets of brushes pass the associated tripping yokes. The circuit referred to extends from battery, through the winding 40 of the relay 61, conductor 74, sequence switch contact 221 (7 $\frac{1}{2}$ to 8), conductor 180, cord finder commutator segment K and its corresponding brush to ground. Relay 61 in operating opens in its left-hand back contact 45 the previously traced circuit by way of conductor 73 which, up to this time, has been holding energized the relay 95 at the 0 operator's position and the relays 93 and 94 corresponding to this position on the cord 50 finder frame. The release of the relay 94 deenergizes the corresponding trip magnet 20 and the common relay 63. The deenergization of the relay 93 reestablishes, subject to the release of relay 61, the control of other 55 finder circuits over the brush-tripping mechanism of the associated cord finder frame.

Relay 61 in operating closes a locking circuit for itself by way of conductor 73, sequence switch contact 218 (6 $\frac{3}{4}$ to 8), and 60 thence to ground. It also completes a circuit that extends from battery through the motor magnet and contact 205 (8) of the sequence switch 200, conductor 75, right-hand front contact and armature of relay 61 65 to ground. The closure of this circuit moves

sequence switch 200 out of position 8. In moving out of position 8, the sequence switch opens its contacts 218 (6 $\frac{3}{4}$ to 8) and 221 (7 $\frac{1}{2}$ to 8), thus deenergizing relay 61 and again extending conductor 73 to the relay 54 70 and the conductors over which the operator's selection is effected. In closing its right-hand back contact upon release, relay 61 also restores the continuity of conductor 76 and makes it available for moving out of position 6 the sequence switch of some other finder circuit which may be waiting for access to the operator's selecting circuit.

When the sequence switch 200 is moved out of position 8, it moves into position 9 80 and there awaits the finding of an idle connecting cord circuit upon the operator's position that has been selected. As the brush-carrying rod moves up, the brushes 111, 112, 113 and 114 of the set that has been tripped come into engagement with sets of terminals 115, 116, 117 and 118 corresponding with the different connecting cord circuits located at that operator's position. When a cord circuit is not in use, its corresponding terminal 118 is connected directly to ground; and when the terminals of such a connecting circuit are encountered, a path is completed that extends from battery, through the lower winding of relay 37, sequence switch contacts 206 (8 to 9), conductor 99, brush 114, terminal 118, conductor 88 of the cord circuit, contact 161, which is closed when the associated cord is not in use, and back contact and armature 95 of relay 119 to ground. Current flowing in this circuit causes the relay 37 to attract its armature and break the previously traced circuit by way of sequence switch contacts 216 and 217 and the right-hand winding of 100 relay 30, which, up to this time, has been holding relay 30 energized. When the relay 30 is released, it opens, in its right-hand front contact, the previously traced circuit including the up-drive magnet 34, and thus 105 causes the brushes of the cord finder switch to come to rest on the terminals of the selected cord circuit. The relay 30 in releasing also closes a circuit that extends from battery through the motor magnet and contact 202 (9) of the sequence switch 200, back contact and right-hand armature of relay 30, and sequence switch contact 218 (8 to 9) 110 to ground. The closure of this circuit moves the sequence switch 200 out of position 9, 115 whereupon it moves under the control of its cam 201 into position 14, which is the talking position of the finder circuit.

It may be seen from the foregoing that the selection of any operator's position that may be available by any finder circuit of the group is effected through the medium of operator's selecting apparatus common to the group of finder circuits and to the group of operators' positions. The interval dur- 120 125 130

ing which each of the finder circuits has operative relation with this common operator's selecting circuit is represented by the time that is occupied by the finder sequence switch in moving from position 4 to position 9. In the normal operation of the system, this interval is short, being merely the space of time required by the finder circuit to test and obtain access to the common selecting circuit, select an idle operator's position, operate the brush trip magnet corresponding with that position, and cause the upward movement of the brush-carrying elevator far enough to trip the corresponding brushes. If for any reason this interval should be unduly protracted, thus delaying the access of other finder circuits to the operator's selecting circuit, or if the operator's selecting circuit should accidentally become inoperative, apparatus is provided for giving prompt notification of such a condition. The indication is given by the lamps 270 and 280, and by the lamp 271 which lights whenever either of the other two lamps lights. The test circuit for the common operator's selecting apparatus is the circuit which extends serially through the sequence switch contacts 219 (9 to 4) of all of the finder circuits of the group. This circuit is normally closed, and in the normal operation of the system is open only while a finder circuit is being served by the operator's selecting apparatus. Included in the normally closed circuit is a relay 273 which is kept energized by the normal current flow in this circuit. When the test circuit by way of the sequence switch contacts 219 (9 to 4) is opened, this relay is deenergized, releases its armature and permits the closure of the associated contacts. But the relay 273 is made slow-releasing, as by providing its core with a copper sheath, so that the closure of the associated contacts occurs a certain interval after the energizing circuit is broken. When the contacts of the relay 273 close, a circuit is completed that extends from battery, through the lamp 270 and the left-hand winding of the relay 272 in parallel, and thence to ground by way of the switch contacts of the relay 273. The completion of this circuit lights the lamp 270 and also energizes the relay 272, which attracts its armature and lights the lamp 271. In the normal operation of the system, the opening of the test circuit in the finder sequence switch contacts 219, when the sequence switch moves out of position 4, is followed promptly by the grounding of conductor 73 by way of contacts 218 (6 $\frac{3}{4}$ to 8) of the finder sequence switch when the sequence switch moves out of position 6 and connects the corresponding finder circuit with the common operator's selecting circuit. The grounding of conductor 73 completes a circuit that extends from battery, through the

winding of relay 281, conductor 73, and sequence switch contacts 218 (6 $\frac{3}{4}$ to 8) to ground. Relay 281 thereupon attracts its armatures and closes a circuit that extends from battery, through the winding of relay 273, left-hand armature and front contact of relay 281, and right-hand armature and front contact of relay 55, the last mentioned relay having been energized by way of conductor 71 and finder sequence switch contacts 218 (5 to 8) when the sequence switch moved into position 5. The interval required by the slow-acting relay 273 to release its armature and close its circuit is made a little longer than the interval required in the normal operation of the system for the sequence switch to move to position 6 $\frac{3}{4}$ and energize relay 281. As a result, the relay 281 normally acts to close the alternative energizing circuit for the relay 273 before the relay 273 has had time to respond to the opening of its normal energizing circuit by way of conductor 70 and the series of sequence switch contacts 219. But if the opening of the circuit by way of conductor 70 is not followed within this definite interval by the closure of the alternative energizing circuit by way of the contacts of relay 281, then the relay 273 permits the closure of its contacts and the lighting of the lamps 270 and 271. Or if, at the time the finder sequence switch moves into position 6 $\frac{3}{4}$ and operates relay 281, the relay 55 for any reason is not energized, then the alternative energizing circuit for relay 273 will not be completed and the lamps 270 and 271 will be lighted to indicate trouble in the circuit.

In the normal operation of the system, each finder circuit should have connection with the common operator's selecting circuit only for a sufficiently long interval to permit the selecting of an operator's position, the starting of the brush-carrying elevator and the tripping of the brushes. The lamp 280 and its associated apparatus are provided to indicate when this normal interval is exceeded. At the moment any finder circuit is connected with the common operator's selecting apparatus through the medium of conductor 73, the relay 281 is energized by way of the circuit extending to ground through contact 218 (6 $\frac{3}{4}$ to 8) of the corresponding finder circuit sequence switch. When the relay 281 operates, it applies a ground to the energizing circuit net-work of the train of slow-acting relays 282, 283, 284 and 285. As a result, the relay 282 operates and closes the energizing circuit for the relay 283, the relay 283 operates and closes the energizing circuit for the relay 284, the relay 284 operates and closes the energizing circuit for the relay 285, the relay 285 locks up and also opens the energizing circuit of the relay 282, that relay releases slowly and

opens the energizing circuit of the relay 283, the relay 283 releases slowly and opens the energizing circuit of the relay 284, the relay 284 releases slowly and closes a circuit that extends from battery through the lamp 280 and from battery through the upper winding of relay 272 in parallel, left-hand armature and front contact of relay 285, back contact and armature of relay 284, and right-hand front contact and armature of relay 281 to ground, thus lighting lamp 280, and operating relay 272 to light lamp 271. The relays of the slow-acting train are organized and operate in the manner disclosed in Patent 1,163,896 to Darragh, issued December 14, 1915. The time intervals involved in the operation of this train of relays in order finally to close the circuit for the lamp 280 are, in the aggregate, greater than the interval required for the finder sequence switch to move from position 6 $\frac{1}{2}$ to position 8 in the normal operation of the system. Therefore, if the system is operating normally, the relay 281 is deenergized and releases its armatures before the circuit closed by way of its right-hand armature and front contact has existed long enough to effect the closure of the branch including the lamp 280 and the right-hand winding of the relay 272. But if, for any reason, any finder circuit holds the common operator's selecting circuit for an unduly long interval, then the lamp 280, and the lamp 271, controlled by relay 272, are lighted to indicate the improper operation of the system.

The conductors 83 and 84, which lead to relay 95 at each operator's position, are the paths over which is completed the selection of the corresponding operator's position by the common selecting apparatus of the different frames having access to that position. The operativeness of these paths and of the associated common apparatus is safeguarded by the emergency apparatus involving the lamps 290 and 291 and the relays 292, 293 and 294. In the normal condition of the system, current flows from battery by way of the winding of relay 95 at the operator's position, conductor 84, the left-hand armatures and back contacts of the relays 93 of the various frames in series, and the winding of slow-releasing relay 292 to ground.

When the operator's position is selected and this circuit broken by the operation of the relay 93, as previously described, the relay 292 is deenergized. As relay 292 is slow releasing, an interval elapses from the time it is deenergized until it permits the closure of its associated contacts. When these contacts are closed, if the relay 95 in the meantime has not been energized, a circuit is completed that extends from battery by way of the left-hand armature and back contact of relay 95, conductor 83, switch contacts of relay 292 and winding of relay

293 to ground. This causes relay 293 to attract its armature and close a circuit that extends from battery, through the winding of relay 294, lamp 291 and front contact and armature of relay 293 to ground. Relay 294 in attracting its armature closes an energizing circuit for lamp 290. A set of relays 292 and 293 and a lamp 291 are provided in connection with the conductors 83 and 84 associated with each operator's position. Only one set is shown in the drawing, the presence of the others being understood. The relay 294 is of low resistance and is common to all of the lamps 291. The lamp 290 is a common lamp and lights whenever any of the lamps 291 is lighted.

The lighting of the lamp 291 occurs only when the circuit conditions are abnormal. In the normal operation of the system, the breaking of the energizing circuit of the relay 292 is accompanied by the energizing of the operator's position relay 95, and the last mentioned relay in operating breaks the continuity of conductor 83 over which current must flow to energize relay 293. Therefore, before the slow-releasing relay 292 can release its armature far enough to close the associated switch contacts, the circuit for relay 293 is broken at contacts of the relay 95.

The relays involved in the emergency circuit part of the organization may be given such resistance values as are convenient, or as readily suggest themselves to those skilled in the art. It may be stated, however, that the following have been found to be suitable resistance values for certain of the relays: relays 251 and 252, 1500 ohms; relay 261, 3200 ohms; relay 22, 23 $\frac{1}{2}$ ohms; relay 273, 1000 ohms; relay 281, 2000 ohms; relay 292, 1500 ohms; relay 95, 23 $\frac{1}{2}$ ohms; relay 293, 2000 ohms; relay 294, 0.45 ohms. The foregoing values are with a 48-volt current supply for the parts of the circuit organization in which these relays are included.

It has been found desirable to provide switches, preferably in association with the emergency signal lamps, for cutting out apparatus that the lamps indicate is operating improperly, and for substituting therefor duplicate groups of apparatus in order to restore service. The switch 310, comprising switch contacts 310-1 to 310-6, inclusive, and the switch 311, comprising switch contacts 311-1 to 311-11, inclusive, are such switches. One of the switches 310 is associated with the group apparatus of each group of lines terminating upon a line finder frame, and a switch 311 is associated with the apparatus common to each line finder frame. When the lighting of a lamp 250 indicates an improper condition of the series group circuits, the switch 310, associated with the group in which the trouble has occurred, may be operated, and in being operated discon-

nects the group apparatus consisting of the relays 19 and 24 and the timing sequence switch 100 of that particular group and substitutes for it in the circuit a duplicate set of apparatus. Only one duplicate or emergency set of group apparatus is provided for the line finder frame, this set being connected with the alternate contacts of all of the switches 310 in the same manner in which the regularly used set is connected with the resting switch contacts, and being substituted by the throwing of the associated switch 310, for whichever set of group apparatus is disconnected.

Similarly, a duplicate or emergency set of apparatus is provided to be substituted for the relays 22, 23, 33 and 65, of the common starting circuit when the switch 311 is thrown. Similar switches for disconnecting the various groups of apparatus in the operator's selecting circuit may be provided to be operated in response to the lighting of the lamps 271 and 280. Where desired, such corrective action may be effected automatically, as in the operation of the relay 244 to render another finder circuit available in case the selected finder circuit fails to start its line finder switch, as previously described.

In order to complete the disclosure of the system in connection with which the invention in its preferred form is here shown, the circuits and operations involved in completing connection with the called line and in disestablishing connection at the end of the conversation will now be described.

The connecting circuit to which the finder circuit is extended in the manner hereinbefore described, is illustrated in the present instance as being a cord-circuit terminating in a connecting plug 170 and including in its talking conductors 85 and 86 the windings of a repeating coil 169 with a bridged battery, and the usual signal controlling relays 171 and 187. The connecting circuit also includes a ringing key 120 by means of which current from the ringing generator 181 may be applied to the circuit of the called line, and a listening key 130 by means of which the connection of the operator's telephone set 147 with the called line may be controlled.

The extension of the finder circuit to the connecting cord brings about, in a manner which need not be described, the actuation of a signal on the associated operator's position which informs the operator that a call is waiting. The operator's telephone is connected with the circuit by means of the listening key 130; and when the operator has learned the number of the line with which the calling subscriber desires connection, he completes the connection by inserting the calling plug 170 into the spring-jack 14 of that line. Before the plug is inserted, a busy

test may be made in the usual way over the path that is shown extending from the tip of the plug by way of the armature and back contact of the relay 175. When the plug is inserted, a circuit is closed that extends from battery through the winding of the relay 119, winding of the relay 175, the coöperating sleeve contacts of the calling plug 170 and spring-jack 14, and the winding of the cut-off relay 11 to ground. The completion of this circuit causes all three relays to attract their armatures, the relay 119 opening the path to ground of conductor 88, thus rendering the connecting cord circuit unselectable, relay 175 disconnecting the tip of the plug 170 from the test conductor and completing the talking circuit of the tip strand, and the cutoff relay 11 disconnecting the line relay 12 of the called subscriber's line. Ringing current from the ringing generator 181 may then be applied to the called subscriber's line by closing the contacts of the ringing key 120.

By means of appropriate mechanism, which is disclosed in the patent to S. B. Williams, Jr., No. 1,304,641, issued May 27, 1919, (application Serial No. 180,634, filed July 14, 1917), and which it is unnecessary to describe as it forms no part of the present invention, the extension of the finder circuit to the connecting cord circuit brings about the opening of the contacts of the switch 161 and the closing of the contacts of the switch 152. The switch 152 corresponds to the left-hand armature and front contact of relay 152 of the above mentioned Williams patent, and the switch 161 corresponds to cam 404 of sequence switch 400 of the Williams patent. The switch 161 in opening its contacts renders the associated cord-circuit unselectable immediately and in advance of the opening of the contacts controlled by the relay 119. The closing of the contacts of switch 152 completes a circuit that extends from battery through the winding of relay 155, switch contacts 152, conductor 87, contact 117 and coöperating brush 113 of the cord selector, conductor 98, contacts 217 (9 $\frac{3}{4}$ to 14) and (12 to 14) of the finder sequence switch, right-hand winding of relay 30, sequence switch contact 212 (12 $\frac{3}{4}$ to 14), conductor 50, brush 42 and contact 46 of the line finder, conductor 53 and winding of cutoff relay 11 of the calling subscriber's line to ground. The current that flows in this circuit keeps the relays 155, 30 and 11 energized during the time that the connection is established. The relay 155 closes a normal break in the ring strand 86 of the talking circuit. The relay 30, as long as it is energized, prevents the finder sequence switch 200 from moving out of its talking position 14. The cutoff relay keeps the branch by way of the line relay 12 disconnected from the calling line.

At the termination of the conversation, the replacing of the telephone receivers on their switchhooks at the calling and called subscribers' stations brings about the display 5 of supervisory signals (not shown) which may be controlled by the cord-circuit relays 171 and 187 in the usual way, and the operator in response to this indication withdraws the calling plug 170 from the spring- 10 jack of the called subscriber's line. The withdrawal of the plug is accompanied by the opening of the contacts of switch 152. This opens the circuit traced in the preceding paragraph including the relays 155, 30 15 and 11, and these relays release their armatures. When relay 30 of the finder circuit releases, it closes a circuit that extends from battery through the motor magnet and contact 202 (8 to 14) of the finder sequence 20 switch, left-hand back contact and armature of relay 30, and armature and back contact of relay 37 to ground. This moves the finder sequence switch out of the talking position 14. When the finder sequence switch reaches 25 position 15, it is moved through that position by means of a circuit that is completed from battery, through its motor magnet and contact 202 (15), right-hand back contact and armature of relay 30, sequence 30 switch contacts 218 (15) to ground. When the line finder sequence switch reaches position 16, a circuit is completed that extends from battery through the down-drive magnet 62 of the line finder switch, and sequence 35 switch contacts 208 (16) to ground. As a result, the brushes of the line finder switch are returned to normal.

When the brushes reach their normal position, a circuit is closed that extends from 40 battery, through the motor magnet and contact 205 (16) of the finder sequence switch, conductor 69, segment Y of the line finder commutator and its corresponding brush to ground. This moves the finder sequence 45 switch out of position 16. In the next resting position 17 of the finder sequence switch, a circuit is closed that extends from battery through the down-drive magnet 35 of the cord selector switch, conductor 90, and sequence switch contact 218 (17) to ground. The closure of this circuit energizes the 50 down-drive magnet 35 and causes the cord selector brushes to return to their normal position. At the end of the downward movement of the brushes, a circuit is closed that 55 extends from battery through the motor magnet and contact 205 (17) of the finder sequence switch, conductor 31, Y segment of the cord selector commutator and corresponding brush to ground. The completion 60 of this circuit moves the finder sequence switch 200 out of position 17, after which it returns to position 1 under the control of its cam 201.

In order that the features to which this 65 invention is directed may be fully and clearly disclosed, it has been necessary to describe them in connection with other features that are the subject of co-pending applications assigned to the same assignee, such applications including the application of S. B. Williams, Jr., Serial No. 75,328, filed January 31, 1916; application of S. B. Williams, Jr., Serial No. 75,329, filed January 31, 1916; application of S. B. Williams, Jr., Serial 70 No. 107,090, filed July 1, 1916; joint application of S. B. Williams, Jr., and R. L. Quass, Serial No. 131,089, filed November 13, 1916; and application of F. A. Stearn, Serial No. 107,540, filed July 5, 1916. Such other features are the subject of claims in the applications mentioned above, and are not claimed 75 in the present application.

What is claimed is:

1. In a call distributing system, the combination with a plurality of lines and a plurality of finder switches for making connection therewith, of a starting relay for starting the movement of a finder switch to connect with a calling line, a controlling circuit for said starting relay, means responsive to the initiation of a call for altering the electrical condition of said controlling circuit to operate said starting relay, an electrical emergency device, a timing device for operating the same a predetermined interval after the electrical condition of said controlling circuit is altered, and means for preventing the operation of said emergency device made active in the operation of said starting relay. 85

2. In a call distributing system, the combination with a plurality of lines and a finder switch for making connection therewith, of a starting relay for said finder switch, an electrical emergency device, a controlling circuit for said starting relay and said emergency device, means responsive to the initiation of a call for altering the electrical conditions of said controlling circuit to operate said starting relay first and said emergency device a predetermined interval thereafter, and means for preventing the operating of said emergency device made operative in the actuation of said starting relay. 105

3. In a telephone system, the combination with a plurality of lines and a finder switch for making connection therewith, of a starting relay for said finder switch, a controlling circuit for said starting relay, said controlling circuit being normally continuous, an electrical emergency device responsive to an interruption in the continuity of said controlling circuit a predetermined interval after said interruption occurs, means responsive to the initiation of a call for altering the normal continuity of said controlling circuit and operating said starting re- 110 115 120 125

lay, and means for preventing the operation of said emergency device made active in the operation of said starting relay.

4. In a telephone system, the combination 5 with a plurality of lines and a finder switch for making connection therewith, of an electrical emergency device, means responsive to the initiation of a call for first starting the movement of said finder switch and 10 then after a predetermined interval operating said emergency device, and means for preventing the operation of said emergency device made active in the starting of said finder switch.

15 5. In a telephone system, the combination with a plurality of lines and a plurality of finder switches for making connection therewith, of an electrical emergency device, means made active in initiating a call for 20 first starting a finder switch and then after a predetermined interval operating said emergency device, and means for preventing the operation of said emergency device made active when all of said finder switches 25 are in use.

6. In a telephone system, the combination with a plurality of lines and a finder switch for making connection therewith, of a starting relay for said finder switch, an electrical 30 emergency device, means actuated in the initiation of a call for operating said starting relay and then after a predetermined interval operating said emergency device, and means for preventing the operation of 35 said emergency device made active in the starting of said finder switch.

7. In a switching system, the combination 40 with a plurality of controlling relays, of a normally continuous controlling circuit extending serially through normally closed contacts of said relays, an emergency device, a controlling magnet therefor having its winding included in a shunt of said contacts and adapted to be operated when the portion 45 of said controlling circuit including said contacts is opened, an electromagnet for preventing the operation of said emergency device, and means for energizing said electromagnet made operative in the operation of 50 any of said controlling relays, whereby said emergency device is responsive to an abnormal opening of said controlling circuit but irresponsible to an opening effected by the operation of said controlling relays.

55 8. In a telephone switching system, the combination with switching apparatus, of a normally continuous controlling circuit therefor, normally closed contacts in one part of said circuit adapted to be opened in 60 the switching operations by group apparatus, normally closed contacts included in another part of said controlling circuit adapted to be opened in the switching operations by common apparatus, two electrical

emergency devices, means responsive to the opening of said controlling circuit associated with the group apparatus for operating one of said devices, means responsive to the opening of the part of the circuit associated with the common apparatus for operating 70 the other device, means responsive to the switching operations controlled by the group apparatus for preventing the operation of the first-mentioned emergency device, and means responsive to the switching operations 75 controlled by the common apparatus for preventing the operation of the last-mentioned emergency device, whereby an abnormal opening of any part of said controlling circuit is indicated by the operation of one or 80 the other of said emergency devices.

9. In a telephone system, the combination with a plurality of lines and a plurality of finder switches for making connection therewith, of a switch for controlling the operative relation of said lines with said finder switches, an electrical emergency device, means made active by any line in calling for first operating said controlling switch and then after a predetermined interval operating said emergency device, means for preventing the operation of said emergency device made active in the operation of said controlling switch, and switching mechanism actuated when all of said finder switches 90 are in use for preventing the operation of said controlling switch and at the same time preventing the operation of said emergency device.

10. In a telephone system, the combination 95 with a plurality of lines and a finder switch for making connection therewith, of a starting relay for said finder switch, means made active by any line in calling for operating said starting relay, a slow-acting electrical emergency device, means made active during the operation of the starting relay for energizing said emergency device, and means made active in the starting of a finder switch for releasing said starting relay before the expiration of the interval required for the operation of said emergency device.

11. In a telephone system, the combination 110 with a plurality of lines and a finder switch for making connection therewith, of a starting relay for said switch actuated by a line in calling, means made operative in the starting of said switch for releasing said starting relay, an emergency device, and means for operating the same made effective by the energization of said starting relay for longer than the normal interval required for starting said finder switch.

12. In a telephone system, the combination 115 with a plurality of lines and a plurality of finder switches for making connection therewith, of a starting circuit for said finder switches, a starting relay under the

control of any line in calling for closing said circuit to start a finder switch, means actuated in the starting of a finder switch for bringing another finder switch into operative relation with said starting circuit and at the same time releasing said starting relay, and switching mechanism operated by an abnormal delay in the release of said starting relay for bringing another finder switch into operative relation with said starting circuit.

13. In a telephone system, the combination with a plurality of call-extending circuits, of a plurality of operators' positions to which calls may be extended, a position-selecting apparatus common to said circuits and positions, a common circuit controlling the establishing of operative relation between said call-extending circuits and said position-selecting apparatus, said circuit being normally continuous when available for use, means actuated by a call-extending circuit during the process of selecting an operator's position for interrupting the normal continuity of said common circuit, an electrical emergency device, and means made active by the interruption of said common circuit for longer than the normal selecting interval for operating said emergency device.

14. The combination with a plurality of telephone circuits, of switch-controlling apparatus common thereto, a test circuit and an energizing circuit for said common switch-controlling apparatus, a slow-acting electrical emergency device responsive to a change in the electrical condition of said test circuit, a magnet associated with each of said telephone circuits and responsive to the normal condition of said test circuit, a switch for each of said telephone circuits adapted when operated to bring the associated magnet into operative relation with said test circuit and change the electrical condition thereof, switch contacts controlled by each magnet for closing said switch-controlling apparatus energizing circuit, and means made operative in the closure of said contacts for preventing the operation of said slow-acting emergency device.

15. In a telephone system, the combination with a plurality of call-extending circuits and a plurality of operators' positions, of position-selecting apparatus common to said call-extending circuits and operators' positions, a test circuit and an energizing circuit for said position-selecting apparatus, a slow-acting electrical emergency device responsive to a change in the electrical condition of said test circuit, a magnet associated with each call-extending circuit and responsive to the normal condition of said test circuit, a switch for each call-extending circuit adapted when operated to bring the associated magnet into operative relation with

said test circuit and change the electrical condition thereof, switch contacts controlled by each magnet for closing said position-selecting energizing circuit, and means made operative in the closure of said contacts for preventing the operation of said emergency device.

16. In a telephone system, the combination with a plurality of call-extending circuits and a plurality of operators' positions, of position-selecting apparatus common to said circuits and positions, a test circuit for controlling the operative connection of said call-extending circuits with said position-selecting apparatus, said test circuit being adapted in its normal electrical condition to permit the operative connection of call-extending circuits with said position-selecting apparatus and to prevent such connection when its electrical condition is changed, means for changing the electrical condition of said test circuit when said position-selecting apparatus is connected with, an electrical emergency device responsive after a definite interval to the changed electrical condition of said test circuit, and means for preventing the operation of said emergency device actuated in the operation of said position-selecting apparatus.

17. In a telephone system, the combination with a plurality of call-extending circuits and a plurality of operators' positions, of position-selecting apparatus common to said circuits and positions, an energizing circuit for said position-selecting apparatus, an electrical emergency device, means associated with each call-extending circuit for closing said energizing circuit and a definite interval thereafter operating said emergency device, and means made active in the operation of said position-selecting apparatus for preventing the operation of said emergency device.

18. In a telephone system, the combination with a plurality of call-extending circuits, of a position-selecting apparatus common thereto, an energizing circuit for said position-selecting apparatus, means under the control of each of said call-extending circuits for closing said energizing circuit, means made operative in the operation of said position-selecting apparatus for opening said energizing circuit, an electrical emergency device, and means for operating the same made effective by the closure of said energizing circuit for longer than the normal interval required for the operation of said position-selecting apparatus.

19. In a telephone system, a plurality of lines, a group of finder switches for making connection therewith, means for starting one of said finders to seize one of said lines when calling, an emergency mechanism effective when the operation of the started finder is

delayed to give a signal and to start a second finder to hunt for the calling line.

20. In a telephone system, a plurality of groups of lines, a group of finder switches 5 for making connection therewith, means for starting one of said finders to seize one of said lines when calling, emergency mechanism effective when the operation of the

started finder is delayed to give a signal and to start a second finder in the same group 10 to hunt for the calling line.

In witness whereof, I hereunto subscribe my name this 24th day of November, A. D. 1916.

SAMUEL B. WILLIAMS, JR.
